UNITED STATES PATENT OFFICE

151,762

DESIGN FOR A TOILET BOWL BRUSH RECEPTACLE

Mike Karagozian, Los Angeles, Calif.

Application August 25, 1947, Serial No. 141,064

Term of patent 7 years

(Cl. D9—2)

To all whom it may concern:

Be it known that I, Mike Karagozian, a citizen of Turkey, residing at Los Angeles, in the county of Los Angeles, State of California, have invented a new, original, and ornamental Design for a Toilet Bowl Brush Receptacle, of which the following is a specification, reference being had to the accompanying drawing, forming part thereof.

Fig. 1 is a front view in elevation of a toilet bowl brush receptacle, embodying my new design;

Fig. 2 is a view in side elevation of the same illustrating it in closed position;

Fig. 3 is a view similar to Fig. 2 but illustrating the toilet bowl brush receptacle in open position;

Fig. 4 is a view in rear elevation of the toilet bowl brush receptacle; and

Fig. 5 is a top plan view of the same.

I claim:

The ornamental design for a toilet bowl brush receptacle, as shown.

MIKE KARAGOZIAN.
